UNITED STATES PATENT OFFICE.

ROBERT CARTER, OF RUSH CITY, MINNESOTA.

GAME APPARATUS.

No. 924,038.

Specification of Letters Patent.

Patented June 8, 1909.

Application filed April 20, 1908. Serial No. 428,126.

To all whom it may concern:

Be it known that I, ROBERT CARTER, a citizen of the United States, residing at Rush City, in the county of Chisago, State of Minnesota, have invented certain new and useful Improvements in Game Apparatus; and I do hereby declare the following to be a full, clear, and exact description of the invention, such as will enable others skilled in the art to 10 which it appertains to make and use the same.

This invention relates to game apparatus and has for its object to provide a simply constructed apparatus adapted to instruct and amuse, and which may be played by two 15 persons.

The invention consists in a dial having radially disposed characters, a pointer movable over the dial, a plurality of single guideways, a double guideway, a figure in each guideway, 20 two rotary members, means for transmitting the motion of the rotary members independently to the pointer, and means for coupling the rotary members to the figures one at a time.

25 The rotary members are preferably formed to represent windlasses provided with representations of sweeps, and the figures movable in the guideways are formed to represent stumps, and connected by cords to the windlasses, the game being characterized as "a stump pulling game", or "the prizestump puller", the prize or object for which the game is played being disposed in the "stump" or figure movable in the double guideway.

35 In the drawings representing the embodiment of the invention, Figure 1 is a plan view of the improved apparatus with the cover removed. Fig. 2 is a longitudinal sectional elevation. Fig. 3 is a transverse section centrally through the apparatus. Fig. 4 is a section through one of the drums. Fig. 5 is a perspective view of one of the movable blocks or "stumps". Fig. 6 is a perspective view of the "double stump" or the prize 40 stump.

The improved device comprises a casing 10 of any suitable size or of any suitable material and preferably formed with an intermediate table or platform 11 and cover 12.

50 The table 11 is divided into two parts preferably transversely and provided with a dial 13 at the dividing point, the dial having radially disposed characters of any desired form, but preferably twelve numerals and with four 55 spaces marked "Pull". Mounted for rotation through the dial is a shaft 14 and carry-

ing a pointer 15 above the dial and a double cord pulley 16—17 below the table. Mounted for rotation in the table 11 near each end of the casing are shafts 18—19, the shaft 18 carrying a drum 20 and the shaft 19 carrying a drum 21, above the table and also provided respectively with cord pulleys 22—23 below the table, and connected by endless cords 24—25 with the cord pulleys 16—17 of 60 the pointer shaft 14, so that the rotary movements of the shafts 18—19 will be communicated to the pointer shaft, as hereafter explained. The drum 20 is provided with an operating arm 26 and the drum 21 is provided with a similar operating arm 27, the drums being in the form of ordinary stump pulling windlasses and the arms being in the form of the sweeps usually employed upon 65 such windlasses.

70 Formed in the table 11 preferably at a central point thereof and opposite the dial 13, is a guideway or slot 28 which extends each side of a center line 29 which is preferably disposed upon the table 11, the guideway 28 75 for the purpose of this description being denoted as the "double guideway", and movably disposed in this guideway is a block 30 which is provided with means for supporting an article which is denominated the "prize", 80 and for which the players contend. For the purpose of illustration, the block 30 is provided with a cavity 31 and a movable closure 32, so that the "prize" may be concealed from the players, and they kept in ignorance 85 of the object for which they are contending until the prize is won, which adds greatly to the interest of the game.

85 Disposed in the table 11 at each side of the dividing line 29 are slots or guideways 33—34, 90 the guideways distributed over the surface of the table, but all the guideways of each side of the table are directed toward one side of the drum which is located upon that side, the double guideway 28 being doubly 95 inclined, as shown, so that each portion is directed toward the drum with which it is associated. Each of the guideways is provided with a block, movable therein, the blocks of the guideways 33 being denoted 35, 100 and the blocks movable in the guideways 34 denoted 36. Each of the blocks is formed with recesses in the sides near the lower part in which the edges of the guideways engage to hold the blocks movably in position, and 105 the "double block" 30 is provided with two small hooks 37—38 at opposite sides, the

hooks adapted to receive the rings 39—40 of pull cords 41—42 leading from the drums, as hereinafter explained. The inner ends of all of the guideways or the ends next to the 5 drums 20—21, are enlarged to permit the blocks to be removed when they reach the ends of the guideways, if required.

The lower ends of the shafts 18—19 are stepped in the bottom of the casing 10 and 10 supported in vertical position by bridge frames indicated at 43—44 while the pointer shaft 14 is likewise stepped in the bottom of the casing 10 and supported by a bridge frame 45.

15 With an apparatus thus constructed, the game is played as follows, and for the purpose of this description, the block 30 will be denoted as the "prize stump", and the other blocks 35—36 as the "stumps" or "pull 20 stumps". Two persons can play the game. The prize stump 30 is first provided with a "prize" which may be of any desired character and may be deposited by a third person and its character not revealed to the players until 25 it is won by one of them at the end of the game. Any suitable means may be employed to determine which of the players shall start first and when that is determined the player thus indicated turns the "sweep" 30 26 or 27 of his side of the table one full revolution, and this movement through the action of the pulleys and cords rotates the pointer 15 but at a greater speed as the pulleys 16 and 17 are smaller than the pulleys 35 22 and 23. The character on the dial over which the indicator end of the pointer stops denotes the number of "stumps" which each player is to pull, who then attaches one end of his cord 41 or 42 as the case may be, to a 40 projection 43 or 44 on his drum 20 or 21 and places the ring 39 or 40 over one of the "stumps" 35 or 36 as the case may be, and rotates the drum by the sweep attached thereto, and thus "pulls" the stump along 45 its guideway until it is within the enlargement at the end, when the "stump" can be removed. The operation is then repeated until the denoted number of "stumps" are "pulled". The other player then rotates 50 his drum and the character over which the pointer stops denotes the number of "stumps" which the second player is to "pull" which he does by means of the drum and cord at his side of the table. The player who first 55 "pulls" all of his "stumps" is the winner, and he connects his cord to the prize stump and "pulls" it to his side and extracts the prize.

Of course it will be understood that the 60 game may be varied to any required extent by devising rules and conditions which will complicate the actions, and so prolong the game. For instance a certain character on the dial might indicate that one player was to 65 surrender one of his pulled stumps to the other,

or vice versa, but such changes in the manner of playing the game do not constitute a departure from the principle of the invention, as no change of the structure is required.

The casing may be of any suitable material 70 and of any required size and any required number of the guideways and blocks may be employed, and any required number of the characters arranged upon the dial.

What is claimed, is:—

1. A game apparatus of the character described comprising a rotary member, means for operating said rotary member, a dial having radially disposed characters, a pointer mounted for rotation over said dial, means whereby the motion of said rotary member is transmitted to said pointer, a plurality of guideways, an object movable in each guideway, and means for coupling said objects one at a time to said rotary member. 80

2. A game apparatus of the character described comprising two rotary members spaced apart, means for independently operating said rotary members, a dial having radially disposed characters, a pointer mounted for rotation over said dial, means whereby the motion of said rotary members is independently transmitted to said pointer, a double guideway, an object movable in said double guideway, a series of guideways associated with each of said rotary members, an object movable in each of said last mentioned guideways, and means for coupling each of said rotary members to its series of associated objects one at a time and also to 95 the object in said double guideway. 100

3. A game apparatus of the character described comprising a table having a plurality of guideways, an object movable in each of said guideways, a member mounted for rotation in said table, a cord connected at one end to said rotary member and wound thereon when the rotary member is actuated and adapted to be connected to said objects one at a time, a dial mounted upon said table and provided with radially disposed characters, a pointer movable over said dial, and means for transmitting the motion of said rotary member to said pointer. 105

4. A game apparatus of the character described comprising a table, two members spaced apart and mounted for rotation on said table, a dial having radially disposed characters, a pointer movable over said dial, a double guideway in said table, an object movable in said double guideway, a series of guideways in said table associated with each of said rotary members, an object movable in each of said associated guideways, and means for coupling each of said rotary members to its series of associated objects one at a time and also to the object in said double guideway. 120

5. A game apparatus of the character described comprising two rotary members 125

spaced apart, means for independently operating said rotary members, a dial having radially disposed characters, a pointer mounted for rotation over said dial, means whereby the motion of said rotary members is independently transmitted to said pointer, a double guideway, an object movable in said double guideway and provided with means for supporting an article, a series of guideways associated with each of said rotary members, an object movable in each of said last mentioned guideways, and means for coupling each of said rotary members to its series of associated objects one at a time and also to the object in said double guideway.

6. A game apparatus of the character described comprising two rotary members spaced apart, means for independently operating said rotary members, a dial having radially disposed characters, a pointer mounted for rotation over said dial, means whereby the motion of said rotary members is independently transmitted to said pointer, a double guideway, an object movable in said double guideway, and provided with a receiving cavity, a closure to said cavity, a series of guideways associated with each of said rotary members, an object movable in each of said last mentioned guideways, and means for coupling each of said rotary members to its series of associated objects one at a time and also to the object in said double guideway.

35 7. A game apparatus of the character described comprising two drums mounted for rotation and spaced apart, a sweep connected

to each of said drums, a dial having radially disposed characters, a pointer mounted for rotation over said dial, means whereby the motion of said rotary drums is independently transmitted to said pointer, a double guideway, an object movable in said double guideway, a series of guideways associated with each of said rotary drums, an object movable in each of said guideways, cords carried by said rotary drums and adapted to be coupled to said associated objects one at a time.

8. A game apparatus of the character described comprising a casing having a top and provided with two sets of single guideways, an object movable in each of said single guideways, a double guideway, an object movable in said double guideway, two shafts spaced apart and mounted for rotation in said casing, a drum carried by each of said shafts, a cord pulley carried by each of said shafts, a dial having radially disposed characters, a shaft mounted for rotation and extending through said dial, a pointer carried by said dial shaft and movable over said dial, two cord pulleys carried by said dial shaft, endless cords between the pulleys of said drum shafts and the pulleys of said dial shaft, sweeps connected to said drums, cords connected respectively to said drums and adapted to be connected to said objects one at a time.

In testimony whereof, I affix my signature, in presence of two witnesses.
